UNITED STATES PATENT OFFICE.

WILLIAM A. SCHMIDT, OF ILION, NEW YORK, ASSIGNOR TO THE REMINGTON AUTOMOBILE AND MOTOR COMPANY, OF SAME PLACE.

CARBURETER.

SPECIFICATION forming part of Letters Patent No. 660,125, dated October 23, 1900.

Application filed December 28, 1899. Serial No. 741,863. (No model.)

To all whom it may concern:

Be it known that I, WILLIAM A. SCHMIDT, a resident of Ilion, in the county of Herkimer and State of New York, have invented certain new and useful Improvements in Carbureters; and I do hereby declare the following to be a full, clear, and exact description of the invention, such as will enable others skilled in the art to which it appertains to make and use the same.

My invention relates to an improvement in carbureters, the object of the invention being to provide a carbureter which can be operated mechanically to regulate the proportionate mixture of air and hydrocarbon.

With this object in view the invention consists in certain novel features of construction and combinations and arrangements of parts, as will be more fully hereinafter described, and pointed out in the claims.

In the accompanying drawings, Figure 1 is a plan view illustrating my improvements. Fig. 2 is a view in section on the line $x-x$ of Fig. 1, and Fig. 3 is an end view.

25 A represents a tank or receptacle provided at one side with an outwardly and upwardly projecting inlet-spout 1 for hydrocarbon, and said spout is closed by a suitable plug or stopper 2. The cover or top 3 for said tank is provided at each side with a downwardly projecting elongated tube 4 and with a cylindrical chamber 5, communicating with each tube 4, and both of said cylindrical chambers 5 converge at their rear ends into a single pipe or tube 6, communicating with the inlet-port of any approved engine. (Not shown.) Each cylindrical chamber 5 is provided with a series of rings 7, spaced apart and secured to the inner face of the cylindrical chambers in any approved manner. A tube 8 is disposed in each cylindrical chamber and is mounted in each series of rings 7 and is preferably of sufficient length to project outward beyond the end of the tank, 40 where said tubes are secured together by means of a cross-head 9. A rack-bar 10 is disposed between the cylindrical chambers 5 parallel therewith and is secured at one end to the cross-head 9. A bracket 11 is disposed 45 on the top or cover 3, and a pinion 12 is mounted on said bracket and meshes with the

rack 10, so that when said pinion is turned it will operate the rack 10 to move the tubes 8 longitudinally in the chambers 5. Each tube 8 is provided at its inner end with an inwardly-projecting beveled flange 13 to form a seat for a beveled check-valve 14. The stem 14^a of said valve 14 is mounted in a bearing 15 in a cross-bar 16, secured to the tube, and a nut 17 is screwed on the end of the valve-stem, and a coiled spring 18 is mounted on the stem 14^a and is adapted to bear respectively against the nut 17 and bearing 15 to hold the valve on its seat.

Suitable packing-rings 19 and 20 are provided in the front end of the chambers 5 to prevent any inlet of air around the outside of the tubes 8.

A wick filling or packing 21 is provided in the tank A, extends upward through the elongated wick-tubes 4 to the bottom of the tubes 8, and is disposed between the lower portions of the rings 7.

The operation of my improvements is as follows: When the parts are in the position shown in the drawings, air drawn through the tubes 8 will not become carbureted, and hence an engine connected with the pipe 6 would not operate. When it is desired to start the engine, the pinion 12 is turned to move the rack 10 and tubes 8 connected therewith outward a sufficient distance to permit the hydrocarbon rising from the wick 21, which is impregnated with the hydrocarbon, to mix with the air and be carried off to any approved engine.

It will be seen that the proportionate mixture of air and hydrocarbon can be regulated by regulating the movement of the tubes 8—as, for instance, when the tubes 8 are moved outward but a short distance the space for mixing air and hydrocarbon is small, and hence the air will contain but a small amount of hydrocarbon. However, as the tubes 8 are moved outward the proportion of hydrocarbon mixed with the air will be correspondingly increased, as will be readily understood.

Various slight changes might be resorted to in the general form and arrangement of the several parts described without departing from the spirit and scope of my invention, and hence I would have it understood that I do

not wish to limit myself to the precise details set forth, but consider myself at liberty to make such slight changes and alterations as fairly fall within the spirit and scope of my 5 invention.

Having fully described my invention, what I claim as new, and desire to secure by Letters Patent, is—

1. The combination in a carbureting apparatus, of a hydrocarbon-chamber, means for passing air over the hydrocarbon-chamber and means for regulating the extent of the hydrocarbon-chamber exposed to the air passing over it.

15 2. A carbureting apparatus having a hydrocarbon-chamber and a chamber above and communicating therewith and an adjustable tube disposed in said upper chamber and adapted to communicate therewith and regulate the extent of the hydrocarbon-chamber exposed to the air passing through said tube.

25 3. In a carbureting apparatus, the combination of a hydrocarbon-chamber and an air-chamber having an elongated opening communicating with the hydrocarbon-chamber, a longitudinally - adjustable tube in the air-chamber and constituting a valve to close communication between the air and hydrocarbon chamber, and a check-valve controlling the outlet of air from said tube.

30 4. In a carbureter, the combination with a tank or receptacle for hydrocarbon and a pipe or tube communicating with the upper portion of said tank or receptacle at one end thereof, of an air-inlet tube in alinement with said first-mentioned tube or pipe, and means for adjusting said air-inlet tube longitudinally.

40 5. In a carbureter, the combination with a tank or receptacle for hydrocarbon and a pipe or tube communicating with said tank or receptacle at one end thereof, of an air-inlet tube in said tank or receptacle in alinement

with said first-mentioned tube or pipe, means for adjusting said air-inlet tube longitudinally, a check-valve in said air-inlet tube and packing-rings between said air-inlet tube and the tank or receptacle. 45

6. In a carbureter, the combination with a tank or receptacle adapted to contain hydrocarbon and a wick filling or packing in said receptacle or tank, of a cover for said tank or receptacle, a cylindrical chamber on said cover communicating with the tank throughout the greater portion of its length, a pipe 55 into which said chamber converges at one end, rings secured in said chamber and spaced apart, an air-inlet tube disposed in said rings, packing-rings between said tube and chamber at one end, a rack connected with said tube and a pinion meshing with said rack and adapted to operate the same and the air-inlet tube to move the latter longitudinally in the cylindrical chamber.

7. In a carbureter, the combination with a tank or receptacle adapted to contain hydrocarbon and a wick-filling, of a cover for said tank or receptacle, parallel chambers on said cover communicating with said tank or receptacle, a pipe at one end of said receptacle into 70 which both of said chambers converge, an air-inlet tube in each chamber having one end projecting therefrom, a cross-head connecting the outer ends of said tubes, a rack connected to said cross-head and a pinion meshing with said rack and adapted to move the tubes longitudinally, substantially as and for the purpose set forth. 75

In testimony whereof I have signed this specification in the presence of two subscribing witnesses.

WM. A. SCHMIDT.
